CLAIM

The ornamental design for a cooling rack as shown and
described.

DESCRIPTION

FIG. 1 is a top perspective view of a cooling rack showing
my new design with legs extended;

FIG. 2 is a bottom perspective view of the cooling rack of
FIG. 1;

FIG. 3 is a top plan view of the cooling rack of FIG. 1;

FIG. 4 is a bottom plan view of the cooling rack of FIG. 1;

FIG. 5 is an end plan view of the cooling rack of FIG. 1;

FIG. 6 is an opposing end plan view of the cooling rack of
FIG. 1;

FIG. 7 is a side plan view of the cooling rack of FIG. 1;

FIG. 8 is an opposing side plan view of the cooling rack of
FIG. 1;

FIG. 9 is a top perspective view of the cooling rack with legs
retracted;

FIG. 10 is a bottom perspective view of the cooling rack of
FIG. 9;

FIG. 11 is a top plan view of the cooling rack of FIG. 9;

FIG. 12 is a bottom plan view of the cooling rack of FIG. 9;

FIG. 13 is an end plan view of the cooling rack of FIG. 9;

FIG. 14 is an opposing end plan view of the cooling rack of
FIG. 9;

FIG. 15 is a side plan view of the cooling rack of FIG. 9; and,

FIG. 16 is an opposing side plan view of the cooling rack of
FIG. 9.
